United States Patent Office

Des. 185,469
Patented June 9, 1959

185,469

MOTION PICTURE CAMERA

Robert L. Smith, Deerfield, and Clark C. Macomber,
Evanston, Ill., assignors to Bell & Howell Company,
Chicago, Ill., a corporation of Illinois

Application March 28, 1958, Serial No. 50,225

Term of patent 14 years

We claim:

The ornamental design for a motion picture camera, as shown.
